UNITED STATES PATENT OFFICE.

WILLIAM HEDRICH AND JOHN LINDEMAN, OF TROCHU, ALBERTA, CANADA.

DRAG.

Application filed January 8, 1921. Serial No. 435,923.

To all whom it may concern:

Be it known that we, WILLIAM HEDRICH, a citizen of the United States, and JOHN LINDEMAN, a citizen of Canada, both residing at Trochu, in the Province of Alberta and Dominion of Canada, have invented certain new and useful Improvements in Drags, of which the following is a specification, reference being had to the accompanying drawings.

This invention relates to certain improvements in drags, and it is an object of the invention to provide a novel and improved device of this general character which can be employed to advantage in packing and leveling the soil.

Another object of the invention is to provide a device of this general character having novel and improved means whereby the same operates to pack the soil smooth and tight without dragging the soil and which can be employed to advantage in packing the soil in hollows.

An additional object of the invention is to provide a novel and improved device of this general character which operates effectively to break the land where there are thistles or stubbles and which treats the land whereby the possibility of drifting is substantially eliminated.

The invention consists in the details of construction and in the combination and arrangement of the several parts of our improved drag whereby certain important advantages are attained and the device rendered simpler, less expensive and otherwise more convenient and advantageous for use, as will be hereinafter more fully set forth.

The novel features of our invention will hereinafter be definitely claimed.

In order that our invention may be the better understood, we will now proceed to describe the same with reference to the accompanying drawings, wherein:

Figure 1 is a view in top plan of a drag constructed in accordance with an embodiment of our invention.

Figure 2 is a view in side elevation of the device as illustrated in Figure 1, with portions broken away, and

Figure 3 is a sectional view taken substantially on the line 3—3 of Figure 1.

As disclosed in the accompanying drawings, our improved device comprises two side or end runners 1 of desired dimensions and which are maintained in desired spaced

relation by an elongated beam or rigid member 2. The end portions of the beam or member 2 rest upon the upper end portions of the runners 1 adjacent the rear ends thereof and are secured thereto by the bolts 3 or the like. It is preferred that each of the bolts 3 be inserted through a runner 1 from below and the opening or bore 4 through which said bolt 3 is directed has its lower portion enlarged, as at *a*, so that the head *b* of the bolt is housed within the runner so that said bolt offers no obstruction to the ground engaging or working edge of the runner.

The beam or member 2 at substantially its longitudinal center also has arranged thereon a seat structure *S*. The forward end portions of the runners 1 are connected by a bar or rod 5 which serves as a pivot or fulcrum common to all of the intermediate runners or slides 6.

The runners or slides 6 are interposed between the runners 1 and substantially fill the space between said runners 1 and each of the runners or slides 6 is capable of independent swinging movement in a vertical direction. As is clearly illustrated in Figure 3 of the drawing, it is to be noted that the runners 1 are of a height greater than the height of the runners or slides 6. The forward end portion of each of the runners or slides 6 is provided with an opening 7 through which the bar or rod 5 is freely directed and whereby said runner or slide 6 is supported for desired swinging movement. The contiguous runners or slides 6 are also closely adjacent to each other.

Hingedly connected, as at 8, with the top face of each of the runners or slides 6 at a point in advance of the beam or member 2 is an end portion of a rearwardly directed elongated strip or bar 9. This bar or strip 9 is of a length to terminate rearwardly of the beam or member 2 and said rear end portion has loosely disposed therethrough an upstanding rod 10 carried by the rear portion of the coacting runner or slide 6. Interposed between said runner or slide 6 and the bar or strip 9 is an expandible member 11, preferably a coil spring encircling the rod 10. The member 11 serves to urge the runner or slide 6 downwardly yet permitting the same to have yielding upward movement.

Suitably secured to the rod or bar 5 is a rigging *R* to which is adapted to be hitched

a team of draft animals. In practice, the runners or slides 6 slightly converge forwardly toward the central runner with the front of the device approximately twelve feet wide and the rear portion about thirteen feet wide, and with a device of such dimensions we find best results can be attained with the use of four draft animals.

As the device is drawn over the soil, each 10 of the runners or slides 6 is capable of independent swinging movement in a vertical direction which is of particular advantage in properly packing the soil in hollows. It has also been found, in practice, that by having the runners or sleeves 6 independently movable, a more effective packing of the soil is effected with a resultant leveling of the ground and which result is especially desirable when a harvesting machine is adapted 20 to be later used.

* Our improved device has also been found to work with advantage in places where there are thistles or stubbles as it will break them up and also level the land. Our improved device also effectively treats the soil 25 to substantially eliminate drifting.

From the foregoing description it is thought to be obvious that a drag constructed in accordance with our invention is particularly well adapted for use by reason of 30 the convenience and facility with which it may be assembled and operated, and it will also be obvious that our invention is susceptible of some change and modification 35 without departing from the principles and spirit thereof and for this reason we do not wish to be understood as limiting ourselves to the precise arrangement and formation of the several parts herein shown in carrying 40 out our invention in practice except as hereinafter claimed.

We claim:

1. An agricultural device of the class described comprising side runners, a rod connecting said runners at the forward end portions thereof, a beam connecting the rear 45

portions of the runners and fixed thereto, a plurality of slides interposed between the runners, the forward portion of the slides being pivotally engaged with the rod, said 50 slides having swinging movement independently of the runners and beam, and means co-acting with each of the slides and the beam for urging the slides downwardly.

2. An agricultural device of the class described 55 comprising side runners, a rod connecting said runners at the forward end portions thereof, a beam connecting the rear portions of the runners and fixed thereto, a plurality of slides interposed between the 60 runners, the forward portion of the slides being pivotally engaged with the rod, said slides having swinging movement independently of the runners and beam, and means co-acting with each of the slides and the beam for urging the slides downwardly, the runners being of a height greater than 65 the height of the slides.

3. An agricultural device of the class described comprising side runners, a rod connecting said runners at the forward end portions thereof, a beam connecting the rear portions of the runners and fixed thereto, a plurality of slides interposed between the 70 runners, the forward portion of the slides being pivotally engaged with the rod, said slides having swinging movement independently of the runners and beam, a bar hingedly connected to each of the runners and extending rearwardly thereof and below the beam, and an expansible member interposed between the slide and the bar to maintain the bar in contact with the beam and to urge the slide downwardly.

In testimony whereof we hereunto affix 85 our signatures.

WILLIAM HEDRICH.
JOHN LINDEMAN.
